UNITED STATES PATENT OFFICE.

FERDINAND F. BISCHOFF, OF MILWAUKEE, WISCONSIN.

EGG-CASE TRAY OR FILLER.

SPECIFICATION forming part of Letters Patent No. 760,842, dated May 24, 1904.

Application filed November 1, 1902. Serial No. 129,641. (No model.)

To all whom it may concern:

Be it known that I, FERDINAND F. BISCHOFF, residing at Milwaukee, in the county of Milwaukee and State of Wisconsin, have invented a new and useful Improvement in Egg-Case Trays or Fillers, of which the following is a description, reference being had to the accompanying drawings, which are a part of this specification.

10 My invention has relation to improvements in egg-case trays or fillers.

The primary object of the invention is to provide a construction whereby by a peculiar cut of a blank of strawboard or other suitable material tray partitions or strips are formed of such construction as not only to effect a great saving of material, but at the same time providing ample means for ventilation and in addition thereto also providing means for permitting ready inspection of the eggs for the purpose of testing without the necessity of removing the eggs separately from the tray, but yet when the necessity for removing does arise said eggs can be removed singly without inconvenience and with the least possible trouble.

A further object resides in the provision of a construction whereby the trays can be folded for transportation, so as to take up the minimum space.

With the above and other incidental objects in view the invention consists of the devices and parts or their equivalents, as hereinafter more fully set forth.

35 In the accompanying drawings, Figure 1 is an elevation of a case, a portion of one of the side pieces thereof broken away, said case having a series of my improved trays or fillers arranged therein one on top of the other 40 with an intervening horizontal layer or supporting-partition between each set of trays. Fig. 2 is a detail fragmentary view of two of the partitions employed in making up the tray adjusted together after having been cut 45 so as to clearly illustrate the line of cut. Fig. 3 is an elevation of a fragment of one of the trays. Fig. 4 is a plan view of a tray. Fig. 5 is a plan view of one of the trays folded for transportation, and Fig. 6 is an edge view of 50 Fig. 5.

Referring to the drawings, the numeral 7 indicates the case for containing the trays or fillers. Each tray or filler consists of a series of parallel partitions or strips 8 of strawboard or other desirable material and another series of intersecting partitions or strips 9 of similar material interlocked with the first-named strips in such manner as to form a series of pockets or receptacles 10 for containing the eggs. The top edges of the sets of partitions are provided at equidistances apart with the recesses 11. The downwardly-cut recesses provide therebetween upwardly-extending projections 12. The recesses are so disposed that when the partitions are adjusted together in the manner illustrated in Fig. 4 each side of each pocket will be provided with one of the downwardly-extending recesses. The partitions are interlocked by providing the upwardly-extending projections 12 of the partitions 8 with downwardly-extending slits 13 and the partitions 9 with slits 14, which extend upwardly for a desired distance from the lower edges of said partitions and in line with the centers of the projections 12 of said partitions 9. In adjusting or locking the partitions together the bordering edges of the slits 13 are made to embrace the opposite sides of the projections 12 of the partitions 9, while the bordering edges of the slits 14 of the partitions 9 embrace opposite sides of the partitions 8 below the projections 12 of said partitions. It will be observed that the lengths of the respective slits are such that when the adjustment referred to is effected the lower edges of the interlocked partitions will be flush and the upper edges of the projections 12 will likewise be flush and that also the respective projections 12 of the partitions are located at the corners or angles 90 of the pockets 10.

The particular manner of forming the partitions is shown in Fig. 2, wherein two of the partitions 8 and 9 are illustrated as adjusted together after having been cut in order to clearly show the line along which the cut was made in order to form two partitions of the particular shape illustrated. The line of cut is indicated by the letter *a*. In order to give the preferable rounded contour to the recesses 100

and projections, the cut is made in sigmoid curves. After being cut in the manner indicated the respective slits 13 and 14 are then made. By this means of forming the partitions there is no waste of material, excepting the small amount of material necessarily cut out in the formation of the slits and a small amount of material which must be cut off at the ends of the blank from which the partitions are cut.

In arranging my improved trays within the case the lower tray rests on the floor of the case, with preferably a loose partition 15 therebeneath, while over the top of each succeeding tray is placed one of the loose horizontal partitions 15, each partition forming the bottom piece for the next upper tray of the series. As each tray is placed in the case it is filled by putting the egg in each pocket.

10. When it is desired to inspect the eggs contained in a tray, all that is necessary to be done is to remove the tray, with its loose bottom piece. The recesses 11 then afford ample opportunity for examining entirely around the eggs and produce registering view-openings in approximately the center of the walls of each cell for testing purposes. If it is desired to examine the eggs from below, a glass or transparent bottom piece may be placed

15 beneath a strawboard partition 15 and said partition then drawn out. By elevating the tray and the transparent bottom thereof the lower ends of the eggs can be readily inspected. The recesses not only facilitate the

20 inspection of the eggs and provide for thorough ventilation thereof, but also permit said eggs to be readily removed singly from the uppermost tray without the necessity of removing said tray from the case, inasmuch as the recesses afford opportunity for the insertion of the fingers, so as to obtain a firm

25 grasp on the eggs.

Besides the advantages already pointed out the invention possesses an additional advantage of providing a construction wherein the trays can be folded, so as to occupy a minimum space during shipment. Figs. 5 and 6

of the drawings illustrate a fragment of a tray folded for shipment. In order to accomplish the folding, all that is necessary is to grasp a tray at diagonally opposite corners thereof and exert an outward pull at such corners. This has the effect of bringing the partitions together flat, as illustrated in Figs. 5 and 6, the interlocking slits acting as hinges to permit of the turning of the partitions. When thus folded together flat, two diagonally opposite outer border-partitions are brought parallel to each other, and the two other diagonally opposite border-partitions are likewise brought parallel and in longitudinal alinement with the first-mentioned partitions, while the inner partitions are brought from their normal intersecting positions to positions in which they are parallel and flat against each other.

What I claim as my invention is--

As a new article of manufacture, an egg-case tray comprising two sets of strips, both sets of strips being similar in shape, having upper edges serrated in regular compound curves producing rounded projections at regular intervals with rounded recesses therebetween extending approximately half-way down the said strips, the rounded projections of one set of strips, however, being provided with central vertical slits extending the full length thereof and the other set of strips being provided with vertical slits centrally beneath the projections and extending from the lower edge of said strips to approximately half the width of the strips, the latter set of strips being placed upon and across the other set of strips with their slits interlocking, thereby forming cells of which all the corners are formed by intersecting projections and all the sides contain the recesses forming registering view-openings.

In testimony whereof I affix my signature in presence of two witnesses.

FERDINAND F. BISCHOFF.
